UNITED STATES PATENT OFFICE.

WILLIAM D. MANN, OF CHICAGO, ILLINOIS.

INTERIOR BUILDING CONSTRUCTION.

No. 810,291.

Specification of Letters Patent.

Patented Jan. 16, 1906.

Application filed June 27, 1904. Serial No. 214,409.

To all whom it may concern:

Be it known that I, WILLIAM D. MANN, a citizen of the United States, residing at Chicago, in the county of Cook and State of Illinois, have invented a certain new and useful Improvement in Interior Building Construction, of which the following is a full, clear, concise, and exact description, reference being had to the accompanying drawings, forming a part of this specification.

My invention relates to interior construction-work for buildings, and especially to the construction of interior walls and fittings.

Prominent objects of the invention are to provide a simple, practical, and inexpensive interior construction for buildings; to permit the walls with their fittings, or "trims," as they are called, to be constructed in a simple and expeditious manner and with a great saving of time and labor as compared with the present construction of such walls; to make the same fireproof, and to secure the foregoing and other desirable results in a practical and effective manner.

In accordance with my invention, I first prepare a completed and finished trim for interior walls, consisting of base-pieces, door-jambs, window-frames, chair-rails, picture-moldings, caps, and similar devices. Part of

the trim, such as the door and window frames and base-pieces, are secured in position and then the wall-frame is erected. Then other parts of the trim—as, for instance, the chair and picture-rails—are secured in position, and then the wall is finished, as by plastering it. If the wall is of tile, such tile is erected and then plastered after the trim is in position. Any other construction of wall can be similarly built. After the wall is erected and finished the trim is cleaned off, if need be, the chances being that more or less plaster will have been splashed or dropped upon it. The wall with its trim is thus completed and the plaster can harden after such completion. It

will be seen that this affords a very cheap and simple construction of wall, and at the same time there is a great saving in time. Ordinarily the wall structure is erected and plastered, and then the plaster allowed to harden before the trim is added. This waiting for the plaster to harden occupies considerable time, which undesirably delays the construction and completion of the building and at the same time affords actual financial loss to

the building owners by delaying the time 55 when the premises can be rented.

In the accompanying drawings, Figure 1 is a side elevation of a wall structure constructed in accordance with my invention. Figs. 2 3, 4, and 5 are sections taken on lines 2 2, 3 3, 60 4 4, and 5 5, respectively, in Fig. 1, on an enlarged scale. Figs. 6 and 7 are views of parts shown in Fig. 1, also on an enlarged scale.

Referring first to Fig. 1, I have shown a wall structure A in elevation, and a cross-wall B in vertical section. The wall A is provided with a door C and windows D D. This wall is also shown provided with a single base-piece 1, a chair-rail 2, and a picture molding or railing 3. The wall B is shown provided 70 with a double base-piece 4, chair-rails 5 5, one on each side, and a double picture-railing conveniently made in the form of a cap 6. The base-pieces 1 and 4 are first prepared and finished and then secured in position upon 75 the floor. The door-jamb 8, forming the frame for the door, is also previously prepared and secured in position. The wall structure is then erected exclusive of the plastering, and the chair-rails 2 and 5 and picture-moldings 3 80 and 6 are secured in position. The wall is then plastered and the trim is cleaned off when the wall is in a completed condition and the plaster is allowed to dry and harden.

The various fittings or trimmings of the 85 base-pieces, the railings, &c., constituting what is commonly known as the "trim," can be of any suitable or desired construction. As a preferred arrangement, however, they are made of sheet metal filled with cement. For 90 example, the single base-piece 1 is formed of a length of sheet metal 9, formed into the proper shape and into a somewhat tubular form and is then filled with concrete 10. The chair-rails 2 and 5 and picture-moldings 3 are 95 similarly formed of sheet-metal strips 11 and 12, filled with concrete 10. The double base-piece 4, the door-jamb 8, and the double picture-molding 6 are likewise formed of sheet-metal strips properly bent and filled with cement; but all of these members are given a socket construction so that a portion of the wall fits into them, as well shown in Figs. 5, 6, and 7. These elements are desirably constructed and finished beforehand in any desired way. The exterior faces of the sheet-metal strips can be varnished or painted or stained to give them the appearance of va-

rious kinds of woods, as desired. This construction, in addition to being inexpensive and durable, is fireproof, so that the whole wall structure will form a fireproof construction.

5 It will be understood that changes and modifications can be made in the structure herein set forth and especially in the particular arrangement and construction of the trim 10 without departing from the spirit of my invention.

What I claim is—

1. The method of erecting and securing in 15 position the interior walls of a building, which consists in first preparing the trim, then placing parts of the trim in position, then erecting the wall exclusive of its plaster, then securing other parts of the trim in place, and then finishing the wall, substantially as 20 described.

2. The method of erecting and securing in 25 position the interior walls of a building, which consists in placing parts of the trim in position, then erecting the wall-frame, then placing other parts of the trim in position, and then plastering to the trim, substantially as described.

3. The method of building interior walls, 30 which consists in first preparing a base-piece, chair and picture rails, then setting the base-piece and picture-rail in position, then erecting the wall-frame, then setting the chair-rails in position, and then plastering the wall-frame, substantially as described.

35 4. The method of building interior walls, which consists in first preparing a base-piece, a door-jamb, picture and chair rails, setting the base-piece and door-jamb in position, erecting the wall-frame, setting the railings 40 in position, and then plastering the wall-frame, substantially as described.

45 5. The method of building interior walls, which consists in first preparing the trim, then setting certain parts of the trim in position on the floor, then erecting the wall-frame, then setting the other parts of the trim by securing them to the wall-frame, and finally finishing the wall-frame, substantially as described.

50 6. The step in the method of erecting and securing in position the interior walls of a

building, which consists in placing parts of the trim in position on the wall-frame, and then plastering to the trim, substantially as described.

55

7. In interior building construction, a trim extending from the wall construction beyond the finish of the wall, whereby the trim can be first secured in position and then the wall finished, substantially as described.

60

8. In interior building construction, a trim consisting of a socket member adapted to receive the wall structure and to extend out beyond the same, in combination with a portion of the permanent wall structure fitting 65 into said socket whereby the trim can be first set and then the wall structure built and finished, substantially as described.

65

9. The method of erecting interior walls, 70 which consists in placing a socketed base-piece, a socketed picture-mold cap, and a socketed door-jamb in position, then building the wall-frame, and then plastering the same.

70

10. The method of erecting interior walls, 75 which consists in placing a socketed base-piece, a socketed picture-mold cap and a socketed door-frame in position, then building the wall, then securing a chair-rail to the wall-frame, and then plastering such frame.

80

11. A trim for building constructions, consisting of a sheet-metal strip formed into the shape of the trim for opposite sides of the same wall, and filled with cement made in socket form to receive the wall structure, substantially as described.

85

12. The combination with an interior building-wall, of trim therefor, extending from the wall-frame through the finish, substantially as described.

90

13. The combination with an interior building-wall, of a trim therefor comprising a socket member adapted to receive the frame construction of the wall and to serve as trim for the opposite side of the wall, substantially as described.

95

In witness whereof I hereunto subscribe my name this 8th day of June, A. D. 1904.

WILLIAM D. MANN.
